ATTORNEY

UNITED STATES PATENT OFFICE.

PAUL WIENER, OF NEW YORK, N. Y.

IRON-STAND.

1,136,455.

Specification of Letters Patent. Patented Apr. 20, 1915.

Application filed February 15, 1915. Serial No. 8,222.

To all whom it may concern:

Be it known that I, PAUL WIENER, a citizen of the United States, and residing at New York, in the county of New York and State of New York, have invented certain new and useful Improvements in Iron-Stands, of which the following is a specification, such as will enable those skilled in the art to which it appertains to make and use the same.

This invention relates to stands or holders for sadirons, and the object thereof is to provide an improved device of this class which is designed to be connected with, or secured to an ironing board and by means of which the use of the iron will be facilitated, and whereby the iron may be handled or manipulated more easily and conveniently than is ordinary with this class of devices.

The invention is fully disclosed in the following specification, of which the accompanying drawing forms a part, in which the separate parts of my improvement are designated by suitable reference characters in each of the views, and in which:—

Figure 1 is a plan view of an ironing board provided with my improvement; Fig. 2 a section on the line 2—2 of Fig. 1 and on enlarged scale and indicating an iron in position on the holder in dotted lines; Fig. 3 a plan view of the iron stand detached and showing a slight modification; and, Fig. 4 a section on the line 4—4 of Fig. 3 and showing the holder attached to a board.

In the accompanying drawing, referring to Figs. 1 and 2, I have shown an ironing-board *a* of the usual form and at *b* I have shown one form of my improved iron stand or holder which consists of a base plate *b*² preferably stamped from sheet metal and provided at its opposite side with front legs *b*³ and rear legs *b*⁴, and the front legs are longer than the rear legs, whereby the base plate *b*, or the stand proper, is supported at an inclination to the board *a*. The rear end of the base plate *b*² which is downwardly inclined is provided with a rear edge portion *b*⁵ which is beveled downwardly and rearwardly on its top surface, and said base plate is provided at the opposite side edges thereof with raised side walls or flanges *b*⁶ which are preferably terminated rearwardly of the front end *b*⁷ thereof, and said front end is also preferably beveled or rounded as clearly shown.

In the rear end portion of the base plate

*b*² are two pairs or sets of transverse slots or openings *b*⁸ and corresponding transverse tongues *b*⁹ on the upper and bottom sides of the plate, and springs *c* are passed through the slots or openings *b*⁸ beneath one of the tongues *b*⁹ and over the other, and the front ends of which project upwardly and forwardly as shown at *c*² in Fig. 2, and in the use of this device the operator whenever necessary or desirable simply slides the iron indicated in dotted lines at *d* in Fig. 2 up into the stand or holder into the position indicated, and between the side walls or flanges *b*⁶, and in this operation the iron passes over the upwardly and forwardly directed ends *c*² of the springs *c* and drops down in front of said ends and is held against either lateral or backward movement, and this operation, or method of operation, facilitates and simplifies the use of the iron as will be readily understood by all those familiar with devices of this class.

In Figs. 3 and 4, I have shown a modification in which the rear end edge portion of the plate *b*² while being tapered as shown in Figs. 1 and 2 is provided with a transverse raised shoulder *b*¹⁰ which takes the place of the springs *c* and, in the form of construction shown, is provided centrally thereof with a V-shaped recess *b*¹¹.

The operation, or method of operating or manipulating the iron will be exactly the same as with the construction shown in Figs. 1 and 2, but the construction shown in Figs. 3 and 4 is provided primarily for use in connection with irons which are tapered at both ends, in which event the rear end tapered portion of the iron fits in the recess *b*¹¹ when the iron is placed in position on the stand or holder. In both forms of construction, the plate *b*², or the body portion of the stand or holder is provided with openings or apertures *b*¹², in the construction shown, which aid in a way to prevent the overheating of the stand or holder, and which also makes said stand or holder lighter when made of metal than it would otherwise be.

My improved iron stand or holder may be stamped from sheet metal, or may be produced by casting, and changes in and modifications of the various details of construction herein described may be made, within the scope of the appended claims, without departing from the spirit of my invention or sacrificing its advantages.

Having fully described my invention, what I claim as new and desire to secure by Letters Patent, is:—

1. An iron stand, comprising a flat body portion having raised side flanges and adapted to be rigidly secured to a board or support in a downwardly and backwardly inclined position, said body portion being provided transversely thereof and forwardly of its rear edge portion with a transverse raised member.
2. An iron stand or holder, comprising a base plate or body portion having raised side flanges and provided with front and rear legs, the front legs being longer than the rear legs, and said device being adapted to be rigidly secured to a board or support in a downwardly and backwardly inclined position with the rear edge thereof resting on said board or support.
3. An iron stand or holder, comprising a base plate or body portion having raised side flanges and provided with front and rear legs, the front legs being longer than

the rear legs, and said device being adapted 25 to be rigidly secured to a board or support in a downwardly and backwardly inclined position with the rear edge thereof resting on said board or support, and the base plate or body portion being provided forwardly 30 of the rear edge thereof with a raised member.

4. An iron stand or holder, comprising a flat body portion adapted to be rigidly secured to a board or support in a downwardly 35 and backwardly inclined position, said body portion being provided with a transverse rear edge which rests on said board or support when the device is secured thereto.

In testimony that I claim the foregoing as 40 my invention I have signed my name in presence of the subscribing witnesses this 11th day of February 1915.

PAUL WIENER.
